DESIGN FOR A TIRE

John E. Allen, Chicopee Falls, Mass., assignor, by
mesne assignments, to United States Rubber
Company, New York, N. Y., a corporation of
New Jersey

Application November 1, 1939, Serial No. 87,998

Term of patent 14 years

To all whom it may concern:

Be it known that I, John E. Allen, a citizen of the United States, residing at Chicopee Falls, county of Hampden, and Commonwealth of Massachusetts, have invented a new, original, and ornamental Design for a Tire, of which the following is a specification, reference being had to the accompanying drawing, forming part thereof.

In the drawing,

Fig. 1 is a side elevational view of a tire with

a sidewall portion in full lines, showing my new design;

Fig. 2 is a fragmentary side elevational view on a larger scale of a portion of the tire shown in Fig. 1; and

Fig. 3 is a section taken along line 3—3 of Fig. 2.

I claim:

The ornamental design for a tire, as shown.

JOHN E. ALLEN.
